(57) CLAIM

I claim the ornamental design for a forked tip hinge pin remover tool, as shown.

DESCRIPTION

FIG. 1 of the drawings is a perspective view showing the front, top, and right side of a forked tip hinge pin remover tool embodying the design of my invention;

FIG. 2 is a top plan view of the forked tip hinge pin remover tool;

FIG. 3 is a side elevation view of the right side of the tool;

FIG. 4 is a front elevation view;

FIG. 5 is a side elevation view of the left side;

FIG. 6 is a back elevation view;

FIG. 7 is a bottom plan view;

FIG. 8 of the drawings is a perspective view showing the front, top, and right side of a second embodiment of a forked tip hinge pin remover tool embodying the design of my invention;

FIG. 9 is a top plan view of the second embodiment;

FIG. 10 is a side elevation view of the right side of the second embodiment;

FIG. 11 is a front elevation view of the second embodiment;

FIG. 12 is a side elevation view of the left side of the second embodiment;

FIG. 13 is a back elevation view of the second embodiment; and,

FIG. 14 is a bottom plan view of the second embodiment.
